UNITED STATES PATENT OFFICE.

THOMAS A. EDISON, OF LLEWELLYN PARK, ORANGE, NEW JERSEY.

DISCHARGING APPARATUS FOR BELT CONVEYERS.

13,434.

Specification of Reissued Letters Patent. Reissued June 25, 1912.

Original No. 861,819, dated July 30, 1907, Serial No. 378,890. Application for reissue filed November 30, 1907. Serial No. 404,827.

To all whom it may concern:

Be it known that I, THOMAS ALVA EDISON, a citizen of the United States, residing at Llewellyn Park, Orange, county of Essex, 5 and State of New Jersey, have invented a certain new and useful Discharging Apparatus for Belt Conveyers, of which the following is a description.

My invention relates to a discharging apparatus for belt conveyers, such, for example, as those in which at each discharging station the belt is passed over supporting rollers so disposed as to form the belt in an S or Z-shape, whereby material may be discharged from the upper run of the belt 15 through conveying chutes or may be discharged on to the lower run of the belt so as to be carried to the next station. In using belt conveyers of this type on an extensive 20 scale in connection with the manufacture of Portland cement, I find that the belts become very rapidly worn, since at each discharging station the material falling from the upper to the lower run of the belt requires to be 25 moved from a state of rest to the speed of the belt, which may be as high as 500 feet per minute. And the same objection is encountered in operating any conveyer where the material is deposited thereon substantially 30 from a state of rest or when moving at a less speed than that of the conveying belt.

The object of my present invention is to provide improvements in discharging apparatus wherein objectionable wear on the belt will be overcome, and to this end the invention consists in providing means in combination with the belt whereby material will be deposited thereon while moving in 40 the direction, and at substantially the surface speed of, the belt.

With a conveyer of the type specifically referred to the invention consists in interposing between the upper and lower runs of the belt at each discharging station a suitable projecting device by means of which the material falling from the upper run of the belt will be projected forwardly so that when it is received by the lower run of the 45 belt its velocity will be substantially coincident therewith. The special form of projecting device which I prefer to employ for this purpose is a drum or roller provided with radial wings on its periphery for receiving and propelling material forward,

and rotated by suitable connections from one of the supporting rollers over which the belt passes at each discharging station.

In order that the invention may be better understood, attention is directed to the accompanying drawing forming part of this specification, and in which—

Figure 1, is a longitudinal sectional view of the apparatus in its preferred form, at one of the discharging stations, as applied to a conveyer of the special type referred to; Fig. 2, a cross-sectional view on the line 2—2 of Fig. 1, and Fig. 3, a diagrammatic view.

In these views corresponding parts are represented by the same numerals of reference.

1 represents a suitable endless conveying belt, which is shown in use in connection with three discharging stations 2, 3 and 4. I refer to the run 5 of the belt entering the discharging station as the upper run, and the run 6 of the belt leaving the same discharging station, as the lower run. At each discharging station the upper run of the belt passes over a pulley 7 and the lower run 80 passes from a pulley 8. Any suitable and well-known arrangement may be employed to give the belt a trough-shape, so as to facilitate the handling of the material. At each station I provide a shelf 9 on which the material may accumulate in a pile 10 (see dotted lines Fig. 1), and extending out from each side of the shelf are chutes 11 having vertical legs 12 which discharge into a suitable stock house. From each of these legs 90 the material will be formed into a pile 13 which when it becomes large enough, will close the mouth and fill up the legs 12 and chutes 11, so as to thereafter overflow the shelf 9 and fall upon the lower run to be 95 carried on to the next station. If, however, it is desired to provide means at each station for cutting off the discharge of material thereat, each chute 11 may be provided with a suitable valve 14 (see Fig. 2) which may 100 be closed when it is desired to cut off the discharge of material.

Heretofore with apparatus of this type the material from the shelf 9 falls vertically on the lower run 6 and requires to be started from rest by the belt, so as to thereby objectionably wear the belt, especially when the material is of a hard, erosive nature, like Portland cement. To obviate this defect, I interpose a device between the upper 110

run 5 and the lower run 6 of the belt and by which the material falling from the upper run will be projected forwardly, so as to preferably coincide with the speed of the belt. This device is preferably a drum or roller 15 formed with radial wings or blades 16, and rotated in any suitable way, as for example by a belt 17 driven from the shaft of one of the rollers 7 or 8, the surface speed 10 of the drum being preferably about the same as that of the belt, so that the material falling from the shelf 9 on to the drum 15 will be projected forwardly (see Fig. 3) so that when it reaches the belt its movement will 15 be substantially coincident therewith.

Having now described my invention, what I claim as new and desire to secure by Letters Patent is as follows:—

1. The combination of a traveling imperforate belt conveyer adapted to carry a stream of separate solid particles of material, a rotating drum or roller mounted adjacent the same, its upper surface moving in the same direction as said conveyer, means 20 for feeding to said roller a stream of solid particles of the width to be carried by the conveyer, said roller having peripheral means adapted to receive said material and cause the velocity of the roller to be imparted thereto and to project the same upon the conveyer, and means for rotating the drum or roller with a surface speed substantially equal to that of the conveyer, whereby wear upon the conveyer due to the discharge 25 30 35 thereon of the solid particles of material is minimized, substantially as set forth.

2. The combination of a traveling imperforate belt conveyer adapted to carry a stream of separate solid particles of material, a rotating drum or roller mounted adjacent the same, its upper surface moving in the same direction as said conveyer, means 40 for feeding to said roller a stream of solid particles of the width to be carried by the conveyer, the arrangement of feeding means and roller being such as to prevent said particles from falling from said roller in a direction contrary to that of rotation, said roller being adapted to receive said material and impart its velocity thereto and to project the same upon the conveyer, and means 45 50 55 for rotating the roller with a surface speed substantially equal to that of the conveyer whereby the wear due to the discharge

thereon of the solid particles of the material is minimized, substantially as set forth. 55

3. In a discharging apparatus for belt conveyers of the type described, the combination with the upper and lower runs of a belt, means located between the upper and lower runs for receiving material discharged from the upper run and projecting it forwardly in the direction of travel of and upon the lower run, substantially as set forth. 60

4. In a discharging apparatus for belt conveyers of the type described, the combination with the upper and lower runs of a belt, of a stationary shelf for receiving the material discharged from the upper run and 65 means located beneath the shelf for receiving material discharged therefrom and projecting it forwardly in the direction of and upon the lower run, substantially as set forth. 70

5. In a discharging apparatus for belt conveyers of the type described, the combination with the upper and lower runs of a belt, of a roller located between the upper and lower runs for receiving material discharged from the upper run and projecting it forwardly in the direction of and upon the lower run, substantially as set forth. 75 80

6. In a discharging apparatus for belt conveyers of the type described, the combination with the upper and lower runs of a belt, of a roller located between the upper and lower runs for receiving material discharged from the upper run, projecting it forwardly in the direction of and upon the lower run and means for driving said roller from the belt, substantially as set forth. 85

7. In a discharging apparatus for belt conveyers of the type described, the combination with the upper and lower runs of a belt, of a roller located between the upper and lower runs for receiving material discharged from the upper run and projecting it forwardly in the direction of and upon the lower run, and a plurality of radial 90 95 wings carried by said roller, substantially as set forth. 100

This specification signed and witnessed this 21st day of November, 1907.

THOMAS A. EDISON.
